UNITED STATES PATENT OFFICE.

WARREN TRAVELL, OF NEW YORK, N. Y.

MATERIAL-HANDLING APPARATUS.

Application filed March 1, 1922. Serial No. 540,297.

To all whom it may concern:

Be it known that I, WARREN TRAVELL, a citizen of the United States, and resident of New York, in the county of New York and 5 State of New York, have invented certain new and useful Improvements in Material-Handling Apparatus, of which the following is a specification.

This invention relates to improvements in 10 material-handling apparatus and more particularly to skip hoists. Hitherto in skip hoist mechanisms, the speed of travel of the skip usually has been the same as the rate at which the hoisting rope was wound on the 15 drum of the power hoist. It is an object of the invention to provide a hoisting and transporting equipment in which while the power hoist is operating at uniform speed, the speed of travel of the skip shall be automatically increased as the skip passes from 20 a steeply inclined portion of its way, or hoist-way, to a less steeply inclined portion, or traverse-way. This permits the use of a moderate speed on the hoist-way where such 25 moderate speed is desirable for the automatic loading of the skip or other purposes and a higher rate of speed on the traverse way thereby reducing the period of the round trip travel of the skip and increasing 30 the handling capacity of the apparatus.

It is also an object of the invention to make an improvement in hoisting and transporting apparatus to the end that the pull of the hoist rope on the power hoist shall be 35 nearly constant at all times whether the skip is loaded or empty and whether running on the hoist-way or on the traverse-way, thereby obtaining a uniform load on the power means and effecting an increase in the economy of operation.

This invention also applies as an additional improvement to my improvement in hoisting and traversing apparatus described in U. S. Letters Patent 1,333,948, dated 45 March 16, 1920. It is also an object of the invention to provide the other advantages which are characteristic of the construction disclosed.

In the accompanying drawings, Fig. 1 is 50 a side elevation illustrating one embodiment of the invention in which the traverse-way is horizontal.

Fig. 2 is an end elevation of same.

Fig. 3 is a side elevation of an arrangement in which the traverse-way is so inclined that its rise is half of its length and

the skip is suspended by two parts of rope while on the hoist-way.

Fig. 4 is a side elevation of a similar arrangement in which the rise of the traverse-way is a third of its length and the skip is suspended by three parts of rope while on the hoist-way.

Fig. 5 is a plan view on a larger scale showing the skip with hoist rope and pull-back ropes.

Fig. 6 is a plan view on a larger scale showing the cross-bar illustrated in Fig. 4.

The drawings show apparatus having a way 1, represented by a pair of rails forming a track. This way has a hoist portion 1' which is vertical or steeply inclined, a traverse portion 1'' which is less steeply inclined or horizontal, and a curved section 1''' connecting these two portions of the way. The skip or bucket 2 is hauled along this way by the hoist rope 3 leading to the power-controlled drum 4. This drum may be driven by any suitable means not shown, such as an electric motor or a steam engine. 80 When the traverse-way is horizontal or nearly so, it is necessary to provide means for hauling the skip backward along the traverse-way. Such a means is shown in Figs. 1, 2, and 5 and comprises a counterweight 5 with rope 6 leading around fixed sheaves 7 and 8 to a cross-bar 9 which is carried by the skip in pockets 10 opening forward, while the skip is on the traverse-way, and which is picked up by the fixed 90 pockets 11 as the skip passes from the traverse-way to the hoist-way and is held by these latter pockets while the skip is on the hoist-way. This pull-back means is more fully described in my U. S. Letters Patent 95 1,333,948 dated March 16, 1920.

Figs. 1, 3, and 4 show a counterweight 12 and a counterweight rope 13 which acts on the drum 4 in a direction opposite to that of the hoist rope 3, thereby producing a balancing effect. Preferably the counterweight should be sufficiently heavy to balance nearly the entire weight of the skip while the skip is on the hoist portion of the way, or else heavy enough to balance the skip and about half of its usual load. In this latter case, the power hoist during the lowering of the empty skip on the hoist-way will be doing the same amount of work as it does in pulling the loaded skip up the hoist way. 110 The number of parts of rope by which this counterweight is suspended may be varied

to suit requirements. Figs. 3 and 4 show the counterweight suspended by two parts of rope which, passing around the sheave 15, attached to the counterweight, has its end fastened at a fixed point 14. In Fig. 1, the rope is shown passing over a fixed sheave 16 and leading to an auxiliary counterweight 17. This arrangement is more particularly described in my U. S. Letters Patent 1,333,948 dated March 16, 1920, and provides a means by which the skip is balanced while on the hoist-way and is relieved of such balancing effect while on the traverse-way.

15 Referring to Figs. 1, 2, 3, and 5, the hoist rope 3 leads from the drum 4 around a sheave 20 carried by the skip and has its end fastened to a cross-bar 9 which may be the same cross-bar as that used in obtaining the pull-back effect or it may be a separate cross-bar if so desired. While the skip is on the hoist-way, this cross-bar is held by fixed pockets 11 and the skip is suspended by two parts of rope. As the skip passes from the hoist-way to the traverse-way, pockets 10 on the skip pick up the cross-bar from the fixed pockets and carry it as the skip moves along the traverse-way thus changing the two-part rope connection to a single-part rope connection and thereby causing the skip to travel along the traverse-way at double the speed which it had on the hoist-way. When the skip passes back from the traverse-way to the hoist-way, the reverse of the above operation takes place.

In Fig. 3, the hoist-way is vertical and the traverse-way is so inclined that the sine of the angle which it makes with a horizontal line is one-half, or, in other words, its rise equals one-half its run per unit of length, and the skip is suspended by two parts of rope while on the hoist-way and pulled by a single part of rope while on the traverse-way. If, with this arrangement, the counterweight is sufficiently heavy to balance the entire weight of the skip and half its load, then the work required of the power hoist will be uniform at all times during the movement of the skip with resulting economy of operation.

Fig. 4 shows an arrangement in which the hoist-way 1' is steeply inclined to the horizontal and the traverse-way 1'' is inclined at such an angle that the rise per unit of length of this portion of the way is one-third of the rise for an equal length of the hoist-way; also, the skip while on the hoist-way is suspended by three parts of rope 3'. This latter effect is obtained by leading the rope from the sheave 20 on the skip around another sheave 22 on the cross-bar 9', shown in greater detail in Fig. 6, and fastening the end of the rope to the skip. The operation of and the effect obtained by this arrangement is similar to that of and by the pre-

viously described arrangement. By the use of additional sheaves on the skip or on the cross-bar or on both, other arrangements of the tackle supporting the skip on the hoist-way may be made and inclinations of the traverse-way and hoist-way other than those mentioned may be adopted. In fact, numerous variations may be made from the specific construction and arrangement of apparatus illustrated without departing from the scope of the invention. It is intended to cover in this patent whatever features of patentable novelty exist in the invention disclosed.

I claim as my invention:—

1. In material-handling apparatus, the combination of a way having two portions, one of which is more steeply inclined than the other; a skip movable in a definite path along said way; a sheave attached to said skip; a power-driven drum; a cross-bar; a hoisting rope leading from said drum around the sheave at the skip to the cross-bar; means attached to the skip for carrying this cross-bar while the skip is on the less steeply inclined portion of the way; and means for relieving the skip of the cross-bar while the skip is on the more steeply inclined portion of the way.

2. In material-handling apparatus, the combination of a way having two portions, one of which is more steeply inclined than the other; a bucket movable in a definite path along said way; a sheave attached to said bucket; a cross-bar; a hoisting rope attached to said cross-bar and leading around said sheave; power means applicable to said rope for drawing the bucket along the way; means attached to the bucket for picking up said cross-bar as the bucket passes from the more steeply inclined to the less steeply inclined portion of the way and for carrying it while on the less steeply inclined portion of the way; and means for relieving the bucket of the cross-bar as the bucket passes from the less steeply inclined to the more steeply inclined portion of the way and for holding it while the bucket is on the more steeply inclined portion of the way.

3. In material-handling apparatus, the combination of a way having two portions, one of which is more steeply inclined than the other; a bucket movable in a definite path along said way; a hoisting rope; power means for controlling the motion of said hoisting rope; means whereby the bucket is suspended by two parts of said rope while on the more steeply inclined portion of the way; and means whereby this two-part suspension is changed as the bucket passes from the more steeply inclined to the less steeply inclined portion of the way, so that the bucket is hauled by only a single part of said rope while on the less steeply inclined portion of the way.

4. In material-handling apparatus, the combination of a way having a vertical or steeply inclined portion and a horizontal or slightly inclined portion; a bucket movable in a definite path along said way; a rope and power means applicable thereto for drawing the bucket along said way; and two devices, registering together, one facing forward attached to the bucket and the other facing likewise fixed at a position which the bucket passes as it moves from the vertical or steeply inclined to the horizontal or slightly inclined portion of the way, each of which devices is adapted to pick up from the other the end of said rope, whereby a shift is made between double-part line connection and single-part line connection of said rope with said bucket.
5. In hoisting apparatus, the combination of a hoisting bucket; a sheave attached to said bucket; a fixed way along which said bucket is moved, said fixed way comprising a steeply inclined section and a slightly inclined section joined together by a curved section; a power-driven hoisting drum; a hoisting rope having one end attached to said drum and leading around the sheave on the bucket; a bar to which the other end of the hoisting rope is fastened; means, located near the curved section of the way, for receiving and holding said bar when said bucket moves from the slightly inclined section to the steeply inclined section of the way; and means attached to or part of the bucket for picking up and carrying said bar when said bucket moves from the steeply inclined section to the slightly inclined section of the way.
6. In material-handling apparatus, the combination of a way having a hoist portion and a traverse portion; a skip adapted to move thereon; a hoist rope and power means applicable thereto for drawing the skip up the hoist-way and forward along the traverse-way; a counterweight and second rope adapted to draw the skip backward along the traverse-way; and two devices, registering together, one fixed facing forward on the skip and the other stationarily fixed facing likewise at a position which the skip passes as it moves from the hoist-way to the traverse-way, each of which devices is adapted to pick up from the other the ends of the hoist rope and counterweight rope, whereby the skip and counterweight inter-act while the skip is on the traverse-way and not while it is on the hoist-way and whereby a shift is made between single-part line connection of the hoist rope with the skip while it is on the traverse-way and two-part line connection of the hoist rope with the skip while it is on the hoist-way.
7. In material-handling apparatus, the combination of a way having a hoist portion and a traverse portion; a skip and means including a rope to move the skip along the way; a sheave attached to the skip, around which sheave the rope passes; a bar attached to said rope, arranged across the way; means on said skip to engage and hold said bar, thereby making a single line connection of the rope to the skip while the skip is on the traverse-way; and fixed means beside the way adapted to engage and hold said bar, thereby making a double line connection of the rope to the skip while the skip is on the hoist-way.
8. In material-handling apparatus, the combination of a way having a hoist portion and a traverse portion; a skip and means including a rope to move the skip along the way; a sheave attached to the skip, around which sheave the rope passes; a bar attached to said rope arranged across the way; and two pairs of pockets, one pair on the skip and the other pair fixed at a point beside the way, said pockets opening forward, the two pairs registering together as the skip passes the fixed point, each pair being adapted to engage said bar while it is held by the other pair at said passing; said pockets being in duplicate on the skip, one on each side of the forward portion thereof and being in duplicate, one at each side of the way at the fixed point with the skip passing between them.
9. In material-handling apparatus, the combination of a way having a hoist portion and a traverse portion; a skip and means including a rope to move the skip along the way; a sheave attached to the skip around which sheave the rope passes; a bar attached to said rope arranged across the way; and means whereby the skip picks up the bar at the top of the hoist-way while moving forward and is freed from said bar at the same point while moving backward.
10. In material-handling apparatus, the combination of a way having a hoist portion and a traverse portion; a skip and means including a rope for moving the skip along the way; a sheave attached to the skip, around which sheave the rope passes; a bar arranged across the way and a sheave attached to said bar, around which sheave the rope passes, its end being fastened to the skip; means attached to the skip for picking up said bar as the skip passes from the hoist-way to the traverse-way and for carrying it while the skip moves along the traverse-way; and means for engaging the bar as the skip passes from the traverse-way to the hoist-way and for holding it while the skip is on the hoist-way; thereby making a single part line connection of the rope to the skip while it is on the traverse-way and a three part line connection of the rope to the skip while it is on the hoist-way.
11. In material-handling apparatus, the

combination of a way having a hoist portion and a traverse portion; a skip adapted to move thereon; a hoist rope and power means applicable thereto for drawing the skip along the hoist-way and traverse-way; means whereby the skip is suspended by a plurality of parts of said rope while on the hoist-way; and means whereby this plural-part line suspension is changed as the skip passes from the hoist-way to the traverse-way so that the skip is hauled by only a single part of rope while on the traverse-way.

12. In material-handling apparatus, the combination of a way having two portions, one of which is more steeply inclined than the other, the rise per foot of run of the more steeply inclined portion being approximately twice the rise per foot of run of the less steeply inclined portion; a skip adapted to move thereon; a hoist rope and power means applicable thereto for drawing the skip along the way; a counterweight; means continuously connecting the counterweight to the skip; means whereby the skip is suspended by two parts of the hoist rope while on the more steeply inclined portion of the way; and means whereby this two-part rope suspension is changed as the skip passes from the more steeply inclined to the less steeply inclined portion of the way, so that the skip is hauled by only a single part of said rope while on the less steeply inclined portion of the way.

13. In material-handling apparatus, the combination of a way having two portions, one of which is more steeply inclined than the other, the rise per foot of run of the more steeply inclined portion being approximately twice the rise per foot of run of the less steeply inclined portion; a skip adapted to move thereon; a hoist rope and power means applicable thereto for drawing the skip along the way, there being a continuation of the hoist rope paid out by said drawing means; a counterweight hanging on said continuation rope for balancing the weight of the skip and half of the load which the skip carries; means whereby the skip is suspended by two parts of the hoist rope while on the more steeply inclined portion of the way; and means whereby this two-part rope suspension is changed as the skip passes from the more steeply inclined to the less steeply inclined portion of the way so that the skip is hauled by only a single part of said rope while on the less steeply inclined portion of the way; whereby the unbalanced rope pull on the power means is equalized at all times whether the skip is loaded or empty and whether on the more steeply inclined portion or on the less steeply inclined portion of the way.

14. In material-handling apparatus, the combination of a way having a hoist portion and a traverse portion; a skip adapted to

move thereon; a hoist rope and power means applicable thereto for drawing the skip up the hoist-way and along the traverse-way; and means whereby the skip is suspended by two parts of rope while on the hoist-way and whereby the skip is drawn along the traverse-way by only a single part of rope.

15. In material-handling apparatus, the combination of a way having a hoist portion and a traverse portion; a skip adapted to move thereon; a hoist rope and power means applicable thereto for drawing the skip up the hoist-way and forward along the traverse-way; means whereby the skip is suspended by two parts of rope while on the hoist-way and whereby the skip is drawn forward along the traverse-way by only a single part of rope; and means for drawing the skip backward along the traverse-way.

16. In material-handling apparatus, the combination of a way having two portions, each of which is so inclined to the horizontal that the rise of one portion per unit of length is a multiple of the rise of the other portion per unit of length; a skip adapted to move thereon; a hoist rope and power means applicable thereto for drawing the skip along said way; and means whereby the pull of the skip on the rope leading to the power means remains constant during the travel of the skip along the two portions of the way.

17. In material-handling apparatus, the combination of a way having two portions inclined at different angles to the horizontal; a skip adapted to move thereon; a hoist rope and power means applicable thereto for drawing the skip along said way; a sheave attached to the skip, around which sheave the rope passes; and two devices, registering together, one facing forward on the skip and the other facing likewise, fixed at a position which the skip passes as it moves from one portion of the way to the other, each of which devices is adapted to pick up from the other the end of said rope, whereby a shift is made between single-part line connection and double-part line connection of said rope with said skip.

18. In material-handling apparatus, the combination of a way comprising a hoist portion, a traverse portion, and a curved section connecting them together; a skip adapted to move thereon; a hoist rope and power means applicable thereto for drawing the skip up the hoist-way, around the curved section, and forward along the traverse-way; a counterweight and counterweight rope for drawing the skip backward along the traverse-way; and two devices, registering together, one facing forward on the skip and the other, facing likewise, fixed at the curved section of the way, each of which devices is adapted to pick up from the other the ends of the hoist rope and counterweight rope, whereby the skip and counterweight inter-

act while the skip is on the traverse-way and not while it is on the hoist-way and whereby a shift is made between single-part line connection of the hoist rope with the skip while it is on the traverse-way and two-part line connection of the hoist rope with the skip while it is on the hoist-way.

19. In material-handling apparatus, the combination of a way comprising a hoist portion, a traverse portion, and a curved section connecting them together; a skip adapted to move thereon; a hoist rope and power means applicable thereto for drawing the skip up the hoist-way, around the curved section, and forward along the traverse-way; a counterweight and counterweight rope for drawing the skip backward along the traverse-way; two devices, registering together, one facing forward on the skip and the other, facing likewise, fixed at the curved section of the way, each of which devices is adapted to pick up from the other the ends of the counterweight rope, whereby the skip and counterweight inter-act while the skip is on the traverse-way and not while it is on the hoist-way; and two other devices, similarly located, each of which latter devices is adapted to pick up from the other the end of the hoist rope, whereby a shift is made 30 between single-part line connection of the hoist rope with the skip while it is on the traverse-way and two-part line connection of

the hoist rope with the skip while it is on the hoist-way.

20. In material-handling apparatus, the combination of a way having a hoist portion and a traverse portion; a skip adapted to move in a fixed path thereon; a hoist rope and power means applicable thereto for drawing the skip up the hoist-way and along the traverse-way; and means whereby the speed of travel of the skip is automatically increased as the skip passes from the hoist-way to the traverse-way, and is automatically decreased as the skip passes from the traverse-way to the hoist-way.

21. In material-handling apparatus, the combination of a way having a hoist portion and a traverse portion; a skip adapted to move in a fixed path thereon; a hoist rope and power means applicable thereto for drawing the skip up the hoist way and along the traverse-way; and means whereby the speed of travel of the skip as it passes from the hoist-way to the traverse-way is automatically increased to a multiple of its speed on the hoist-way, and is correspondingly decreased as the skip passes from the traverse-way to the hoist-way.

Signed at New York, in the county of New York and State of New York this 15th day of February A. D. 1921.

WARREN TRAVELL.
